UNITED STATES PATENT OFFICE

99,789

DESIGN FOR A BLOUSE

Sidney Goldstein, New York, N. Y.

Application March 9, 1936, Serial No. 61,536

Term of patent 7 years

To all whom it may concern:

Be it known that I, Sidney Goldstein, a citizen of the United States, residing in the county of New York, city, and State of New York, have invented a new, original, and ornamental Design for a Blouse, of which the following is a specification, reference being had to the accompanying drawing, forming a part thereof.

Fig. 1 is a front view of a blouse showing my new design with the front portions in lapel position.

Fig. 2 is a front view thereof, showing the front portions in closed position.

The back of the garment is of conventional design.

I claim:

The ornamental design for a blouse, substantially as shown and described.

SIDNEY GOLDSTEIN.
